United States Patent Office

Des. 210,925

Patented Apr. 30, 1968

210,925

TIRE

Raymond P. Hawkinson, Minneapolis, Minn., assignor to
Paul E. Hawkinson Company, Minneapolis, Minn., a
corporation of Minnesota

Filed May 9, 1966, Ser. No. 2,232

Term of patent 14 years

(Cl. D90—20)

FIG. 1 is a fragmentary view in perspective of a tire showing my new design, it being understood that the full line portions are reported throughout the circumference of the tire shown by means of broken lines;

FIG. 2 is a view in transverse section thereof as seen from the line 2—2 of FIG. 1.

The dominant features of my design reside in the portions shown in full lines.

An important feature of the design is the circular cross section of the tread and the grooves which are parallel to the straight grooves in the tread and disposed on opposite sides of the tread to provide the curved shoulders of smaller radius than the radius of the tread.

I claim:

The ornamental design for a tire, substantially as shown and described.
